SAFETY RAZORS

Edwin Jacobsen, Altadena, Calif.

Application August 24, 1953, Serial No. 375,868

3 Claims. (Cl. 30—74.1)

This invention relates to safety razors and wafer type blades wherein a substantially one piece razor is adapted to hold a perforated blade at a flat shaving attitude. The razor at the same time exerting a tension in the blade intermediate of said perforations and thereby increasing substantially the natural frequency of the blade.

Since the apertures by which the blade is retained and stretched are parallel to and close to the cutting edges, the tensioning of the blade offers resistance to any rotation of the cutting edges about the retaining prongs of the razor.

In conventional safety razors the blade is more or less free to rotate about the blade retention point, thus the distance between the safety guard and the cutting edge often becomes larger or less than desired for safety and good shaving. Further, since the natural frequency of a conventional wafer type blade is very low inherently, it follows that the amplitude due to the normal driving forces exerted upon it will be high. This too, further aggravates the variation of distance between the cutting edges and the guard.

The above conditions are overcome in my present invention, by stressing the blade in tension from 40,000 to 50,000 p. s. i., the natural frequency is increased many fold and the amplitude is decreased proportionately.

In existing razors it is the practice to grip the blade on either side of its flat surfaces in a manner to present its cutting edge in a properly spaced relationship with the safety guard. In the case of double edged blades, they are often curved and held adjacent to the guard members. In my invention the razor co-acts with the blade to hold the blade in a flat plane in such a manner that it is free to vibrate. However the blade is held under tension or stretched so to speak, by a predetermined force varied by the movement of a handle slide. This varying of the blade tension changes the rate at which the blade will vibrate when the cutting edge contacts an obstruction or severs a hair.

While a blade that is curved and under tension offers some very fine advantages, it has been found that a blade held flat under tension obviates the shear forces and blade cutting edge distortion due to antielastic bending obviously present in the curved blade. Further, the flat unbent blade held in the manner shown, resists the rotation of the cutting edge about the hooks by the tension in the intermediate portion of the blade interposed between the hooks.

The adjustment of the blade tension may be varied by moving the runner along the handle of the razor. That is, the tension in the blade may be increased or decreased by positioning the runner which exerts a constant pressure against the handles.

An object of the invention is to provide a one piece razor adapted to change the natural frequency of a thin wafer type blade by preloading it in tension.

A further object of the invention is to provide a razor that will positively grip and retain a razor blade in tension without the use of screw threads.

2

A further object of the invention is to provide a razor that will hold the blade in a flat plane while under tension.

5 A further object of the invention is to provide a razor that may be rapidly rebladed and readily and easily cleaned.

With these and incidental objects in view, the invention consists in certain novel features of construction and combination of parts, a preferred form of which is hereinafter shown with reference to the drawings which accompany and form a part of this specification.

In the drawings:

Fig. 1 is a top enlarged view of the assembled razor.

Fig. 2 is a cross sectional view taken on line 2—2.

15 Fig. 1.

Fig. 3 is a cross sectional view similar to Fig. 2, except that the runner is near the hinged end of the handle and the blade shown in a removed position.

20 Fig. 4 is an enlarged plan view of the blade, removed to show the apertures in which the hooks engage.

Referring more particularly to the drawings, the upper handle 1, and the lower handle 2, are hinged together at one extreme end by the pin 3. These handles are channel shaped in cross section and form a box like 25 chamber in which the runner 4, operates. This runner has the concave surfaces 5 and 6, for thumb and finger grip when it is to be moved. The rollers 7, contact the inside surfaces 8, of the handles which are parallel for a major portion of the handle length. The springs 9, cause the rollers to exert a predetermined constant pressure against the surfaces 8, for any position throughout the parallel length of the handles.

30 The upper handle has the blade engagement hooks 10, and the lower handle blade engagement hooks 11, which 35 are integrally formed with the handle. The cutting edge guard 12 and the edge rotector 13 are also integral with the handles. The blade 14, has a multiplicity of apertures 15 which the hooks 10 and 11 engage.

35 By moving the runner 4 to the enlarged portion of the handle near the hinge pin 3, as shown in Fig. 3, the handle may be pressed together overcoming the tension of the spring 16. This action brings the hooks 10 and 11 closer together. As the runner 4 is moved to any position in the parallel portion of the handle as shown in 40 Fig. 3, it is obvious that we now have two simply supported beams with a load, represented by the springs 9, acting equally and oppositely between them. It can be shown that by moving the load, the runner 4, along the handles that the load on the hinge pin 3, will increase if 45 the runner is moved in the direction of the pin. It also follows that in this case the load on the blade 14 will decrease. Moving the runner toward the blade as shown in 50 Fig. 2 will decrease the load on the pin 3, and increase the tension load on the blade 14. In this manner, with a constant load against the handles, it is possible to 55 modulate the load and consequently the p. s. i. loading on the blade, thus it is possible to vary the frequency of the blade to meet various conditions.

55 While the form of mechanism herein shown and described is admirably adapted to fulfill the objects primarily stated, it is to be understood that it is not intended to confine the invention to the form of embodiment herein shown and described as it is susceptible of embodiment in various forms all coming within the scope of the claims which follow.

60 What I claim is:

1. In a combination with a wafer type perforated blade, 65 a razor consisting of a pair of handle elements hinged together near one extreme end, blade engagement hooks disposed near the other extreme end of the handle elements, said handle elements being substantially symmetrical channel shaped members normally parallel to

each other through the major portion of their length when said hooks engage with the blade, said one end of the handle elements sloping so as to produce opposing angles to the normal parallel portion of said handle elements, a spring loaded runner having finger grips slidably disposed in the channels between said handle elements and adapted to exert a constant predetermined outward pressure on the parallel surfaces of the handle elements, said runner constituting means for varying the tension loading on the engaged blade.

2. In combination with a flat wafer type blade adapted to be held in predetermined tension, a razor consisting in an integral guard and lower handle element, blade engagement elements integrally formed from said guard element, an upper handle element with integral blade attachment elements at its outer end, said upper and lower handle elements hinged near the extreme end in such a manner that when the blade is on the attachment elements said handles are substantially parallel, a pre-loaded runner slidably disposed between the handle elements for securing the blade to the razor by forcing the handle elements apart and constituting means for varying the tension exerted on the blade by movement of the runner.

15

20

3. In combination with a wafer type thin double edged blade, a razor consisting of an upper handle element, a lower handle element and a spring loaded runner, said handle elements having channel shaped portions hinged together near one end, the other ends terminating in the blade engagement and guard elements, said channel shaped portion providing parallel surfaces when said blade is in place, said runner slidably disposed within the channel shaped portions of the handles, exerting a constant outward pressure along the parallel surfaces when the blade is in place, said parallel surfaces angling outwardly from the runner near the hinge end of the handles, providing an area in which the runner may be placed when installing and removing the blade.
